UNITED STATES PATENT OFFICE.

WILLIAM CLAUD ELLIOTT, OF WHITE OAK, OKLAHOMA.

TABLE.

1,052,329.

Specification of Letters Patent.

Patented Feb. 4, 1913.

Application filed June 29, 1912. Serial No. 706,659.

To all whom it may concern:

Be it known that I, WILLIAM CLAUD ELLIOTT, a citizen of the United States, residing at White Oak, in the county of Craig and State of Oklahoma, have invented new and useful Improvements in Tables, of which the following is a specification.

This invention relates to tables, and has for an object to provide a portable device 10 of this character which can be readily folded to occupy a compact package, when it is desired to carry the table from place to place.

Another object of the invention is to provide means for securely holding the legs of the table folded against one side of the top of the table.

In the drawings: Figure 1 is a bottom plan view of the table, showing the legs folded against one side of the table top. Fig. 2 is a longitudinal section through the table, showing the same set up. Fig. 3 is a perspective view of one of the elements of the leg retainer. Fig. 4 is a similar view of 25 the other element of the retainer. Fig. 5 is a section taken through both elements of the retainer, showing the means for holding the element in locked position.

The table herein illustrated comprises a 30 top 1 which is provided at its corners with legs 2, that are hinged at 3 to the top, whereby the legs can be folded against one side of the latter, as shown in the drawings. At the center of the table is a substantially 35 disk retaining element 4 which is provided with radial recesses 5 for the reception of the free extremities of the legs 2, when the latter are folded against the top 1. To the element 4 is pivoted, as at 6, a companion 40 locking element 7, which is provided with radial recesses 8 that may be brought into registration with the recesses 5 of the first element 4, whereby the said free extremities of the legs 2 can be operatively extended 45 into the said recesses 5. As stated, the element 7 is revolvably mounted upon the element 4, and as illustrated, intervening portions 9 between the recesses 8 of the element 7 are adapted to be extended across

the open sides of the recesses 5, so that the 50 legs will be held against pivotal movement.

The element 7 of the leg retaining device is provided with a sliding stem 10 which is arranged with one of its extremities in frictional contact with a surface 11 of the element 4, a spring 12 upon the element 7 being associated with the stem 10, so as to bend to move the same in the direction of the said surface 11. An actuating button 13 on the stem 10 may be engaged by the hand to facilitate the adjustment of the member 7.

With a view to holding the table set up, I provide locking devices 14 adjacent to the 65 corners of the table, and as shown, these devices are adapted to engage with the legs 2, so as to hold them against pivotal movement.

From the construction of the table described, it is evident that the legs 2 may be 70 readily folded to support the table in a set up position, or they may be folded to lie against one side of the top 1, whereby the table is rendered extremely compact to permit of its being carried from place to place. 75

What is claimed is:

1. A table, a member secured to the under side of the table at the center thereof and provided with diametrically disposed recesses, pivoted legs carried by the table and 80 disposed directly opposite said recesses and adapted to be terminally swung into the recesses whereby the legs will lie directly against the under side of the table top, rotatable means carried by said centrally located member of the top and provided with recesses adapted to align with the first recesses and provided intermediate of the recesses with portions adapted to close the first recesses whereby to confine the table 90 legs in said first recesses.

2. A table, a member secured to the under side of the table at the center thereof and provided with diametrically disposed recesses, pivoted legs carried by the table and 95 disposed directly opposite said recesses and adapted to be terminally swung into the recesses whereby the legs will lie directly

against the underside of the table top, rotatable means carried by said centrally located member of the top and provided with recesses adapted to aline with the first recesses and provided intermediate of the recesses with portions adapted to close the first recesses whereby to confine the table legs in said first recesses, means for holding the legs against pivotal movements, and

means for holding the second recessed member in adjusted position. 10

In testimony whereof I affix my signature in presence of two witnesses.

WILLIAM CLAUD ELLIOTT.

Witnesses:

CLARENCE W. JONES,
C. L. RICHEY.
